FLOW HEAD WITH ADJUSTABLE FLOW BEAN

Donald R. Knowlton, Bartlesville, Okla., and Paul C. Murphy, Shreveport, La., assignors to Phillips Petroleum Company, a corporation of Delaware

Application May 3, 1938, Serial No. 205,814

2 Claims. (Cl. 138—45)

This invention relates to improvements in control apparatus of a type suitable for controlling the fluid flow from oil, gas, and distillate wells or the like.

5 In the process of controlling high pressure wells in fields where large volumes of sand are carried in the well fluid, it is customary to use a flow head with adjustable flow bean structure for choking and controlling the flow of fluid from 10 the well. Equipment of this type eliminates the serious cutting out of flow-head structures which resulted from the abrasive contact with the sand particles under high velocity flowing conditions.

It is of fundamental importance in the design 15 of these flow heads and adjustable flow beans that turbulence in the flow be prevented. This is accomplished by eliminating any expansion chamber within the flow head structure and by producing a stream line flow of the fluids.

20 In addition to this, present governmental regulations have made it necessary to restrict the flow of wells to a predetermined volume. Usually this is a certain proportion of the maximum output obtained under specified conditions.

25 To comply with these proration requirements it is necessary to have control apparatus so designed that a micrometer adjustment may be obtained in relation to the volume of fluid flowing. In this way it is possible to so adjust the 30 flow from the well that the summation of each day's run at the end of the month will exactly equal the proration allowable for that month. This method of operating the wells is more efficient, from a standpoint of conserving the 35 reservoir energy and recovering the petroleum, than a method of producing that requires the wells to be entirely closed in for a part of each month.

40 In accordance with this, the primary purpose of the present invention is to improve the device disclosed in the D. R. Knowlton U. S. Patent No. 1,831,713, dated November 10, 1931, and the Knowlton and Defenbaugh U. S. Patent No. 1,911,905, dated May 30, 1933.

45 An important object of this invention is to provide a control device which can be adjusted to a very fine degree.

Another object of this invention is to provide 50 a flow bean which can be made to cooperate with a number of various sized flow restricting members.

Another object of this invention is to provide 55 a flow bean which will not be readily subject to the cutting action of the sand particles in the fluid.

A further object of the invention is to provide a means for quickly and conveniently removing a flow restricting member from the cross member.

Other objects and advantages of the invention 5 will be apparent during the course of the following description.

In the accompanying drawing, forming a part of this specification, and in which like numerals are employed to designate like parts throughout 10 the same.

Figure 1 is a part vertical sectional view and a part elevational view along the longitudinal axis of one embodiment of this invention, and

Figure 2 is a central, vertical, longitudinal section through a flow restricting member suitable for proration purposes.

In the drawing, wherein for the purpose of illustration, are shown preferred embodiments of this invention, the numeral 5 designates a 20 cruci-form fitting which forms communicating vertical and horizontal passages 6 and 7. Passage 6 and passage 7 may each be considered as being formed of a pair of oppositely disposed 25 communicating passages in the projecting portions of the cruci-form fitting. This fitting 5 is adapted to be connected to a well conduit, either directly over the well bore or at any preferred place in the discharge flow lines, by means of the aligning internally-threaded, opposite, 30 open ends 8 and 9.

Open end 10, externally threaded at 12 and internally threaded at 13 to receive a tubular flow collar or member 14, forms a horizontal fluid conduit.

The open end piece 11, bored as at 15 to receive the body stud bolts 16, forms a supporting base for the body member 18 and provides a recessed passage 7 into which the flow bean 33 may be withdrawn when necessary to run a swab 40 through the vertical passage 6. Passage 7 is of sufficient diameter to allow a free movement of the flow bean 33 and the stem 23, and to afford a convenient access to the flow restricting member 14 when body member 18 is removed.

A ring gasket 17 is placed between the end piece 11 and the flanged head 19 of body member 18 to insure a fluid tight closure between them when the body stud bolts 16 are drawn up tightly.

Removably attached to the end piece 11 by stud 50 bolts 16, or any other means commonly used for this purpose; such as, a screw threaded coupling, is a body member 18. Body member 18 consists of a flanged head 19, which is preferably circular in cross section and bored to receive the study 55

bolts 16, and integrally formed arms or ribs 20 extending from the flanged head portion 19 to a boss 21 located at the outer end of the arms.

As shown in Figure 1, the boss 21 is preferably 5 constructed as an integral part of the arms 20 and is internally threaded to receive a threaded portion 22 of the flow bean stem 23.

An indicator arm 26 is mounted on one of the arms 20 in accordance with common practice.

10 Means for moving the flow bean 33 to open or closed position includes a flow bean stem 23 preferably secured in the body member 18 so as to be free to rotate either in a clockwise or counterclockwise direction. To prevent leakage from 15 occurring along the flow bean stem 23 a packing 21 and a packing gland 28, surrounding the flow bean stem, are mounted between the arms 20 and secured to the body member 18 by means of packing box studs or in any other well known manner.

20 The usual hand wheel 25 is fastened to the extreme outer end of the flow bean stem, by a nut 34, for rotating the flow bean stem to move the flow bean 33 axially to and from its seat.

A stem lock 24 mounted upon the flow bean 25 stem is optional as is the calibrated sleeve 35 and the indicator 26. However, these refinements tend to insure a positive and accurate action of the device although they are not indispensable to operation.

30 Arranged at the extreme inner end of the flow bean stem 23 is a flow bean 33. In the preferred embodiment, flow bean 33 is removably attached to the flow bean stem either through the use of a threaded connection or a pin coupling as in 35 common practice. If desired, the flow bean may be made as an integral part of the flow bean stem. As shown, flow bean 33 is composed of a tapered and conical element 29 which merges into a plurality of frusto-conical members 30, 31, 32, 40 each of which is of greater transverse diameter than the preceding one.

Element 29 is designed with a very slight taper so that a relatively great degree of rotation of the stem 23 will produce a micro-adjustment of 45 the element 29 in relation to the flow member in which it is to cooperate. Figure 2 shows a flow member constructed for proration purposes which is designed to receive the element 29.

The elements 30, 31, and 32 are each designed 50 to cooperate with flow restricting members having progressively greater discharge passages. It is to be understood that the flow bean 33 is not limited to the four members 29, 30, 31, and 32 as shown but can be composed of as many different co-acting members as desired. In this manner it is possible to use a single flow bean with a multiple of flow restricting members and to control the flow of fluid to any degree desired.

We have found in previous flow heads that 60 the cutting resulting from the abrasive action of the sand carried in the fluid was confined to the flow beans and flow restricting members. Where the flow bean is designed with an abrupt or very obtuse point as in former devices, the 65 fluid flow is not confined in a stream line but has a tendency to spray out and become a turbulent flow with the resulting cutting of the flow bean and restricting members.

In our present invention we minimize this 70 cutting through the use of the above described flow bean 33. The combination of the conical element 29 and the frusto-conical elements 30, 31, 32 produces a stream line flow of the fluid and prevents turbulence.

Numerical 14 indicates a flow collar or restrict-

ing member removably mounted by means of the screw threads 13 in the cross member 5. Member 14 is preferably of tubular construction as indicated by the numeral 14-A in Figure 2, having its outer surface threaded at 13 in Figure 1 and 5 13-A in Figure 2. A discharge passage 35, provided within the flow restricting member, connects the interior of the vertical passage 6 with the discharge lines which are adapted to be coupled to element 10 by means of a threaded connection at 12. As will be readily understood by those skilled in this art the transverse diameter of the discharge passage 35 may vary from a minute opening suitable for proration flow to one equal to the wide open diameter of the discharge 15 member 10.

Previous methods of mounting flow restricting members have all been to construct the tubular element with a slight taper so that the restricting member would be held in place by a wedging 20 action. Our method of construction enables us to remove the flow restricting member through the enlarged horizontal passage 7 without disconnecting the flow lines at 12 as was formerly required.

25 The operation of this fluid control apparatus is as follows:

Cruci-form fitting 5 is mounted by means of the aligning internally-threaded open end 9 on an externally threaded well conduit, not shown 30 in the figures, in the customary manner. A closure element such as a bull plug or valve controlled conduit is inserted in the internally threaded open end 8.

End piece 11 is uncovered by removing the 35 flanged body member 18. This in turn allows the stem 23, flow bean 33, and flow restricting member 14 to be withdrawn from the cruci-form fitting 5.

A flow restricting member, 14-14-A, having 40 the proper sized discharge opening 35-35 to allow a desired volume of fluid to pass through, is mounted within the internally threaded open end 10. The external threads of the flow restricting member and the internal threads of the 45 end piece 10 engaging as at 13, Figure 1, in accordance with common practice.

When body member 18 is re-assembled and mounted as shown in Figure 1, flow bean stem 23 can be rotated by means of the hand wheel 25. 50 In this manner, the flow bean 33 is retracted into the horizontal passage 7 until it assumes the position denoted by reference numeral 33-A so that the vertical passage 6 can be cleared of 55 obstructions, or adjusted in relation to the flow restricting member, 14-14-A so as to control the fluid flow being discharged from member 10.

It is to be understood that the manner in which the flow bean 33 cooperates with the flow restricting member 14 determines the amount of 60 discharge opening available for the passage of fluid from the vertical passage 6 into the end member 10.

From the foregoing, it is believed that the construction, operation, and advantages of the invention may be readily understood. It is also to be understood that the form of our invention, herewith shown and described, is to be taken as a preferred example of the same, and that various changes in the shape, size, and arrangements of parts may be resorted to, without departing from the spirit of our invention, or the scope of the subjoined claims.

We claim:

1. In a flow head the combination comprising 75

means for regulating fluid flow through a conduit having vertical and horizontal passages, one of said horizontal passages adapted to have a flow collar mounted therein, the other said horizontal passage having closure means in which is adjustably mounted a flow bean stem, a flow bean connected to said stem, said flow bean including a series of frustro-conical portions for selective cooperation with flow collars having openings corresponding in size to any selected one of said frustro-conical portions.

5 2. In fluid control equipment of the type described, the combination comprising a hollow cruci-form flow head which forms communicat-

ing vertical and horizontal passages, vertical and horizontal open ends in the flow head connected by said passages, one of said horizontal passages adapted to have a flow collar mounted therein, the other said horizontal passage having closure 5 means in which is adjustably mounted a flow bean stem, a flow bean connected to said stem, said flow bean including a series of frustro-conical portions for selective cooperation with flow collars having openings corresponding in size to 10 any selected one of said frustro-conical portions.
